UNITED STATES PATENT OFFICE.

HAROLD C. HARLAN AND WALTER J. ZIMMERMAN, OF DAYTON, OHIO.

DISPLAY WINDOW.

Application filed March 10, 1921. Serial No. 451,398.

This invention relates to display windows for store rooms and the like.

The object of the invention is to provide means for maintaining a continuous display of merchandise in a store window, without the loss of time usually required to remove one display and retrim the window.

A further object of the invention is to provide such a display window which will not encroach upon the floor space of the store room and will not in any way interfere with the normal activities in the store during the trimming of the window.

A further object of the invention is to provide such a display window which will be dust proof.

A further object of the invention is to provide such a window which will be very simple in its construction and operation and which can be easily manipulated to change the displays.

Other objects of the invention will appear as the mechanism is described in detail.

In the accompanying drawings Fig. 1 is a front elevation of a portion of a store front, partly broken away to show the display compartments and operating mechanism for the window; Fig. 2 is a sectional view taken vertically through a display window embodying the invention and broken away to show the operating mechanism; Fig. 3 is a transverse sectional view taken on the line 3—3 of Fig. 2 looking in the direction of the arrows; Fig. 4 is a transverse sectional view taken on the line 4—4 of Fig. 2 looking in the direction of the arrows; and Fig. 5 is a sectional detail view of the dust proof joints for the compartments.

In these drawings we have illustrated one embodiment of our invention and have shown the same as comprising a plurality of display compartments arranged one above the other and mounted for vertical movement to enable the compartments to be moved alternately into line with the window opening. By arranging the compartments one above the other the window occupies no more floor space than does the ordinary display window and because of the vertical movement of the compartments the idle compartment will lie either below the floor so that it will be accessible from the basement for the purpose of removing and inserting the display or it will lie above the level of the window opening and, therefore, in the

upper portion of the store room where access can be had to it by means of a platform or balcony for removing or inserting the display. The arrangement of the compartments may take various forms and they may be moved into and out of display positions in various ways and it will be understood that the particular embodiment here illustrated has been chosen for the purpose of illustration only.

In that form of the invention here illustrated we have shown the same as installed in a store room having the usual floor 1 and ceiling 2 and provided in its outer wall with a window opening, or sight opening, 3, through which the display may be viewed from the exterior of the building, and this sight opening is of a height much less than the height of the ceiling, the opening being usually not more than half the height of the ceiling. The space between the top of the sight opening and the ceiling may be closed in any suitable manner, as by a colored or ground glass, as shown, at 4. Arranged in the rear of the sight opening 3 is a plurality of display compartments, 5 and 6, arranged one above the other and each complete in itself. Each compartment is of a size substantially equal to the size of the sight opening and is open on its forward side only so that its contents can be viewed through the sight opening. These two compartments are mounted for movement alternately into and out of line with the sight opening so that while one compartment is in display position the other can be trimmed. Preferably the two compartments are rigidly connected one to the other and are mounted for movement in a vertical line so that they will move successively into and out of display position. As here shown, the two compartments are built into a single structure and will, of course, be moved simultaneously. This structure is mounted for vertical movement in a guideway 7 which extends vertically above and below the sight opening 3 and which is here shown as completely enclosed, after the manner of an elevator shaft. The display structure, containing the two compartments may be mounted in the guideway in any suitable manner but, as here shown, it is provided on each side with two or more pairs of angle bars 8 arranged back to back and spaced apart to form guide ways to receive flanges 9 of guide strips rigidly secured

100
105
110

to the wall of the main guideway or shaft. The angle bars 8 extend from top to bottom of the structure and serve not only as guides but also serve to rigidly tie together the upper and lower parts of the structure and to impart sufficient rigidity to the structure as a whole, so that other bracing is unnecessary. Further, the interlocking guides and guideways 8 and 9 form barriers which prevent the passage of dust about the sides of the compartments.

To further prevent dust entering the compartments, particularly the one that is on display, the front wall of the shaft, or main guideway, is provided at the upper and lower edges of the sight opening with inwardly extending flanges or sealing members 10 and 10^a, which are here shown as rigid projections each having a covering of flexible material, such as felt, and which are adapted to be engaged by the top and bottom walls of the compartment which is on display and thus form dust proof joints at these points. The sealing members are arranged between the top and bottom walls of the respective compartments and are so positioned that when the lower compartment is in display position the bottom wall of that compartment will engage the lower sealing member 10^a, as shown in full lines in Fig. 2, and in dotted lines in Fig. 5, and the bottom wall of the upper compartment will engage the upper sealing member 10, as shown in Fig. 2. When the upper compartment is in display position the top wall of the lower compartment will engage the lower sealing member 10^a, as shown in Fig. 5, and the top wall of the upper compartment will engage the upper sealing member 10. In this manner the compartment which is on display is made dust proof and the compartment may be moved from one position to the other without the necessity of the top or bottom walls thereof passing the sealing members.

The display structure may be supported in the shaft or guide way 7 and movement imparted thereto in any suitable manner, but it is desirable that this be accomplished in such a way as to avoid the necessity of mounting the supporting or operating mechanism on the top of the structure as it would there interfere, in some cases, with the elevation of the structure to the desired height, it being understood that the upward movement of the structure is usually definitely limited by the ceiling of the room in which it is mounted. We have, therefore, mounted on each side of the shaft, or main guideway, 7 a plurality of sheaves or pulleys 11 about which extend cables 12. One end of each cable is connected with the outer wall of the display structure between the upper and lower ends thereof and, in the present instance, the structure is provided with angle

plates 13 secured thereto at the level of the floor of the upper compartment and one end of each cable is connected with one of these angle plates. The other end of each cable is connected with a weight 14 slidably mounted on suitable guides 15 on the side wall of the main guideway or shaft. It will be understood that this mechanism is duplicated on the two sides of the supporting structure and that the combined weight of the two weights 14 is slightly less than the ordinary weight of the display structure when the latter is fully trimmed. Consequently, when free to move, this structure will move downwardly of its own accord but its movement will be slow and easily controlled. The downward movement of the display structure is controlled and upward movement imparted thereto by means of other cables 16 connected with the respective weights 14, extending downwardly about drums 17 arranged in the basement of the store room and thence to a drum 18, which is here shown as mounted on a vertical shaft 19 to the upper end of which is secured a worm wheel 20 meshing with a worm 21 mounted on a shaft 22 which extends through one of the walls of the main guideway, or shaft, 7 and is provided with a handle, or crank, 23 by means of which it may be operated. The worm and worm wheel not only provide a very simple and easily operated mechanism for actuating the display structure but they also provide an automatic lock as the worm can not be rotated by pressure of the worm wheel. If desired, the shaft, or main guideway, may be provided with locks 24 to positively secure the compartments in display position. When the upper compartment 6 is in display position the lower compartment will project below the floor 1 of the store room and will be readily accessible from the basement for the purpose of removing the old display and placing the new display in position 105 therein, it being understood that the compartment itself and the inner wall of the shaft are provided with doors through which this access may be had, as shown at 26 and 27, respectively, in Fig. 3. When the lower compartment is moved into display position the upper compartment will lie in the upper end of the shaft near the ceiling of the store room and in order that access may be readily had thereto we prefer to provide a platform, 120 or balcony, 25 arranged along the inner wall of the shaft on substantially the level of the floor of the upper compartment so that access may be readily had thereto. This balcony, or platform, being arranged above the sight opening of the window will, of course, be above the head level of the store room and will not interfere in any way with the movements of persons in the store or with the placing of display cases or counters along 130

the inner wall of the display window. Preferably that portion of the shaft in line with the sight opening of the window has no opening therein as it is not usually desired to enter the shaft or the display compartments from the floor of the store.

The operation of the device will be readily understood from the foregoing description thereof and it will be apparent that we have provided a display window of such a character that merchandise can be maintained continuously on display therein, the only lost time being the very short interval required to shift the compartments to move one of them out of display position and the other into display position. While this may be accomplished very easily the movement is slow and steady and the compartment with the new display will be brought into its display position without jar or jolt, which might tend to displace either the merchandise or the display cards which have been placed therein. The arrangement and manner of shifting the display compartments is such that the window does not encroach in any way upon the floor space of the store room and does not interfere with the normal activities within the store room. Further, the display window is of such a character that that compartment which is out of display position can be trimmed without interfering with the normal activities in the store room because in the one instance it is trimmed from the basement and in the other instance it is trimmed from the balcony 25. Moreover, it will be apparent that the device is exceedingly simple in its construction and inexpensive of installation and, further, that it can be easily installed in existing buildings without necessitating any material modification therein. The display compartments are so nearly counterbalanced by the weights 14 that they are easily moved by hand power through the worm gearing described, but it will be obvious that if it should be desired a motor or other power mechanism may be utilized for shifting the structure from one position to another.

While we have shown and described one embodiment of our invention we wish it to be understood that we do not desire to be limited to the details thereof as various modifications may occur to a person skilled in the art.

Having now fully described our invention

what we claim as new and desire to secure by Letters Patent, is:

1. In a display window having a sight opening provided with a transparent closure, a closed housing arranged in the rear of said opening and extending above and below the same, a plurality of display compartments mounted for vertical movement in said housing, said compartments being normally closed on all sides except that side adjacent to said sight opening, and means to prevent the passage of dust about said compartments.

2. In a display window having a sight opening, a closed housing arranged in the rear of said opening, extending above and below the same, a structure mounted for vertical movement in said housing and having a plurality of display compartments adapted to be moved alternately into and out of line with said sight opening, sheaves mounted on the side walls of said housing, cables extending about the respective sheaves and each connected with said structure between the ends thereof, weights on the opposite sides of said structure connected with the respective cables, a drum mounted on the lower portion of said housing, cables connected with the respective weights, and passing about said drum, and means for actuating said drum.

3. In a display window having a sight opening, a closed housing arranged in the rear of said opening, extending above and below the same, a structure mounted for vertical movement in said housing and having a plurality of display compartments adapted to be moved alternately into and out of line with said sight opening, sheaves mounted on the side walls of said housing, cables extending about the respective sheaves and each connected with said structure between the ends thereof, weights on the opposite sides of said structure connected with the respective cables, a drum mounted in the lower portion of said housing, cables connected with the respective weights and passing about said drum a worm wheel connected with said drum, a worm meshing with said worm wheel, and means for rotating said worm.

In testimony whereof, we affix our signatures hereto.

HAROLD C. HARLAN.

WALTER J. ZIMMERMAN.
